UNITED STATES PATENT OFFICE.

TEMPEL L. KINNE, OF DALLAS, TEXAS, ASSIGNOR TO THE MURRAY COMPANY, OF DALLAS, TEXAS, A CORPORATION OF TEXAS.

BOLL BREAKER AND CLEANER.

1,231,171.

Specification of Letters Patent. Patented June 26, 1917.

Application filed April 26, 1915. Serial No. 23,812.

To all whom it may concern:

Be it known that I, TEMPEL L. KINNE, a citizen of the United States, residing at Dallas, in the county of Dallas and State of Texas, have invented certain new and useful Improvements in Boll Breakers and Cleaners, of which the following is a specification.

My invention has relation to a machine for handling and cleaning seed cotton prior to its delivery to the ginning mechanism, such machines being generally known as boll breakers and cleaners and in such connection it relates more particularly to the arrangement and construction of the machine when said machine is adapted for use with a pneumatic conveyer leading to the gin.

In an application for patent filed by me under date of April 1st, 1915, and Serial No. 18,629, I have described and claimed a boll breaker and cleaner which in mechanical details of construction is similar to the boll breaker and cleaner embodied in my present invention. In my former application, however, the boll breaking and cleaning mechanism was so functionally arranged as to perform the function of an air separator within the structure, inasmuch as the cotton and air were broken and cleaned on the exterior of a perforated drum and the air was separated by its passage through the screen to the interior of the drum from whence it was axially or centripetally conveyed and discharged.

In my present application the cotton is introduced to the exterior of a revolving support such as a drum or roller or shaft, the wall of which is imperforate and is subjected to the combined boll breaking and cleaning or to the cleaning operation alone, between the exterior of the revolving support and a screen wall, the cotton being stirred and pressed over the screen wall by paddleblades projecting from the periphery of the support. The cotton after being operated upon is removed from the end of the cleaner through a pneumatic tube or conveyer. The entrance of cotton under suction, its treatment under suction and its discharge under suction are all performed centrifugally of the machine, that is to say, away from the axis of rotation of the support and paddles.

In the carrying out of my invention, I employ certain instrumentalities the preferred form of construction and arrange-

ment of which is illustrated in the accompanying drawing, in which—

Figure 1, is a top or plan view partly in horizontal section, of a boll breaking and cotton cleaning apparatus embodying main features of my invention.

Fig. 2, is an enlarged, longitudinal sectional view, thereof.

Fig. 3, is a cross-sectional view, taken on line $z-z$ of Fig. 2.

Fig. 4, is a cross-sectional view, taken on line $y-y$ of Fig. 2, and

Fig. 5, is a cross-sectional view, taken on line $x-x$, of Fig. 2.

Referring to the drawings 1 represents the external frame for the apparatus which, for convenience in manufacture and the assemblage of parts, is preferably of substantially pentagonal outline, with a point of the pentagon pointing downward to form a trash trough 2 wherein a trash conveyer 3, of any well known construction, is designed to operate. At preferably the inlet end of the apparatus, this trough 2 discharges into a pipe 4 having its exterior end closed by a collapsible valve 5 also of well known form. The outside frame 1 is built up of alternate wood and metal parts which form an essentially air tight compartment or chamber.

Within the frame 1 and supported therein in any suitable manner is a tubular wall or casing 6 extending longitudinally from end to end of the apparatus. Within the chamber formed by the wall or casing 6 is arranged the boll breaking and cleaning mechanism. This mechanism in its preferred form comprises a shaft 7 traversing the chamber axially and carrying a series of frames or spiders 8. The extremities of the arms of said spiders 8 are connected by the longitudinally extending beams 9 to which the plates 10 are secured, said plates constituting the imperforate wall of a drum revolving with the shaft 7. In the preferred form of construction the wall or periphery of the drum is hexagonal, although the wall may be circular if desired and the drum may be a solid shaft or roller of any required diameter with an imperforate periphery. The beams 9 also constitute supports for paddle blades 11, which project from the drum, roller or shaft constituting a revolving support toward the casing 6. The work-

ing tips 12 of the blades 11 are bent spirally with respect to the periphery of the drum to thereby assist in forcing the cotton through the apparatus.

5 At the left hand end of the apparatus the blades 11 are set relatively close together and coöperate with a breast 13 to constitute the boll breaker. The breast 13 is preferably of slatted construction and forms a portion of the lower part of tubular casing 6. A breast regulating device illustrated in Fig. 5 consists essentially of a strap or straps 14 hinged at one end as at 15 to a rod 16 passing through and supported by the exterior frame 1 said straps arranged to constitute the support for the slats of the breast 13. The straps 14 are secured to a block 17, and a worm or screw shaft 18 working in a portion of frame 1 serves to raise and lower the block 17 to elevate or raise said breast 13, and thereby adjust it with respect to the paddle blades 11.

20 At the cleaning portion of the apparatus the paddles 11 are spaced farther apart and coöperate with a screen 19 forming a part 25 of casing 6 and extending from a point where breast 13 terminates to the outlet end of the apparatus. The screen 19 is approximately circular.

30 The inlet to the apparatus comprises a box-like structure 20 supported on the top of the external casing 1 and substantially fan-shaped in plan view. The broad base of the fan discharges downwardly into casing 1, the opening 21 from box 20 extending longitudinally so as to cover the entire boll breaking section and substantially the major portion of the cleaning portion of the apparatus. The contracted mouth 22 forming the 35 entrance to the box-like inlet 20 communicates directly with a chute or flue 23 and said chute 23 is provided with means whereby it may be shifted in box 20 in a direction longitudinally of the apparatus so that chute 23 may connect the mouth 22 with any portion 40 of the discharge 21 from the box 20.

45 As explained more fully in my former application, this arrangement of chute or flue 23 permits of the discharge of cotton to any 50 point of the apparatus so that said cotton, if required, may be subjected to both boll breaking and cleaning means or to cleaning means alone to a more or less extent of that portion of the apparatus as the condition of 55 the cotton requires.

60 The preferred form of swinging chute 23 in box 20 is illustrated in Fig. 1. The front end of chute 23 is hinged as at 24 to the mouth 22 and a rack 25 and pinion 26 controlled by hand wheel 27 may be used to shift the chute, to the varying positions illustrated in full and dotted lines or to intermediate positions as required.

65 The outlet 28 for the cotton is at the periphery of the casing 6 and terminates in a

flue 29 leading to pneumatic conveyer or pipe 30, wherein suction is created by a fan or other suitable instrumentality.

The inlet 20 and outlet 28 are preferably in the same plane.

75 In the operation of the apparatus the cotton under suction is drawn into the apparatus and delivered to the exterior of the revolving support between the exterior of said support and the casing 6.

80 If the cotton is directed to the boll breaker, the paddles 11 coöperate with breast 13 to break the bolls and the paddles also serve to advance the cotton to the cleaning portion of the apparatus. In the cleaning portion the paddles 11 coöperate with screen 19 to force the loose particles of dirt 85 out of the cotton by centrifugal force and mechanical manipulation. In both operations the cotton is treated centrifugally or peripherally of the support, and is finally forced by paddles 13 to the outlet 28 from whence it is drawn under suction assisted by centrifugal force to the flue 29.

90 Having thus described the nature and objects of my invention what I claim as new and desire to secure by Letters Patent, is,—

1. In a device of the character described, a combined boll breaking and cleaning mechanism comprising a breast and a screen 95 wall constituting a casing and a housing inclosing said casing, a support revolving within the casing and provided with an imperforate wall, a series of paddle blades projecting from the imperforate periphery at 100 one end of said support and coöperating with said breast, and a series of paddles projecting from the remaining portion of the support and coöperating with the screen portion of the casing.

105 2. In a device of the character described, a combined boll breaking and cleaning mechanism comprising a breast and a screen wall constituting a casing and a housing inclosing said casing, a support revolving 110 within the casing and provided with an imperforate wall, a series of paddle blades projecting from the imperforate periphery at one end of said support and coöperating with said breast, and a series of paddles projecting from the remaining portion of the support and coöperating with the screen portion of the casing, said paddles being arranged spirally around the imperforate wall 115 of said support.

120 3. In a device of the character described, a combined boll breaking and cleaning mechanism, comprising a breast and a screen wall constituting a casing and a housing inclosing said casing, a support revolving within the casing and provided with an imperforate wall, a series of paddle blades projecting from the imperforate periphery at one end of said support and coöperating with said breast, and a series 125

of paddles projecting from the remaining portion of the support and coöperating with the screen portion of the casing and a means for introducing cotton under 5 suction to the space between the casing and the wall of the support.

4. In a device of the character described, a combined boll breaking and cleaning mechanism, comprising a breast and a 10 screen wall constituting a casing and a housing inclosing said casing, a support revolving within the casing and provided with an imperforate wall, a series of paddle blades projecting from the imperforate periphery at one end of said support and coöperating with said breast, and a series of 15 paddles projecting from the remaining portion of the support and coöperating with the screen portion of the casing and a means 20 for introducing cotton under suction to the space between the casing and the wall of the support, and an outlet for the device arranged to permit of the centrifugal discharge of the cotton and air under suction 25 from the cleaning mechanism.

5. In a device of the character described, a combined boll breaking and cleaning mechanism comprising a breast and a screen wall constituting a casing and a housing in- 30 closing said casing, a drum revolving with-

in the casing and provided with an imperforate wall, a series of paddle blades projecting from the imperforate periphery at one end of said drum and coöperating with said breast, and a series of paddles projecting from the remaining portion of the drum and coöperating with the screen portion of the casing. 35

6. In a device of the character described, a combined boll breaking and cleaning mechanism, comprising a breast and a screen wall constituting a casing and a housing inclosing said casing, a drum revolving within the casing and provided with an imperforate wall, a series of paddle blades projecting 40 from the imperforate periphery at one end of said drum and coöperating with said breast, and a series of paddles projecting from the remaining portion of the drum and coöperating with the screen portion of the 45 casing and a means for introducing cotton and air under suction to the space between the casing and the wall of the drum, and an outlet for the device arranged to permit of the centrifugal discharge of the cotton from 50 the cleaning mechanism. 55

In testimony whereof I have signed my name.

TEMPEL L. KINNE.
